UNITED STATES PATENT OFFICE

173,318

PIE TRAY OR SIMILAR ARTICLE

Alvin W. Levenhagen, Pine Township,
Crawford County, Pa.

Application March 24, 1954, Serial No. 29,673

Term of patent 7 years

(Cl. D44—10)

To all whom it may concern:

Be it known that I, Alvin W. Levenhagen, a citizen of the United States, residing at Pine Township, in the county of Crawford and State of Pennsylvania, have invented a new, original, and ornamental Design for a Pie Tray or Similar Article, of which the following is a specification, reference being had to the accompanying drawing, forming part thereof.

Figure 1 is a perspective view of a pie tray or similar article, showing my new design;

Figure 2 is a side elevational view thereof; and

Figures 3 and 4 are cross-sectional views, on an enlarged scale and taken substantially in the

plane of the lines 3—3 and 4—4, respectively, in Figure 1.

I claim:

The ornamental design for a pie tray or similar article, as shown.
